UNITED STATES PATENT OFFICE.

FRED A. STANDIFORD, OF KANSAS CITY, MISSOURI.

DESIGN FOR A COMBINATION LIGHT FIXTURE AND SPEAKER.

Application filed August 27, 1928. Serial No. 27,975. Term of patent 7 years.

To all whom it may concern:

Be it known that I, FRED A. STANDIFORD, a citizen of the United States, residing at Kansas City, county of Jackson, State of Missouri, have invented a new, original, and ornamental Design for a Combination Light Fixture and Speaker, of which the following is a specification, reference being had to the accompanying drawing, forming a part thereof.

In the drawing the figure shown represents a perspective view of a combination light fixture and speaker, showing my new design.

I claim:

The ornamental design for a combination light fixture and speaker, as shown.

FRED A. STANDIFORD.
